UNITED STATES PATENT OFFICE.

OLIVER O. APP, OF NEW YORK, N. Y.

POWER-ACTUATED IMPLEMENT.

1,253,561.

Specification of Letters Patent. Patented Jan. 15, 1913.

Application filed March 5, 1912. Serial No. 681,754.

To all whom it may concern:

Be it known that I, OLIVER O. APP, a citizen of the United States, residing at New York city, in the borough of Manhattan and State of New York, have invented certain new and useful Improvements in Power-Actuated Implements, of which the following is a full, clear, and exact description.

This invention relates to a novel method 10 of operating tools and to an improved fluid pressure operated implement for chisels, gouges and the like; said method and implement being especially adapted for use in driving tunnels, shafts and in operations 15 generally upon rock and like surfaces.

In my application for United States Letters Patent, Serial No. 669,718, renewed Jan. 5, 1912, I have shown an implement of this 20 general description, and the herein described construction is the result of considerable experimentation looking toward the further development of said implement.

In a certain sense therefore the present 25 invention is an improvement upon my earlier construction; but it involves more than a mere improvement in certain particulars, in that new principles of operations are utilized.

In all other fluid pressure tool actuating 30 devices of the type in question, with which I am acquainted, it has been common practice to admit live air, or the like, back of the hammer or plunger, when the latter is upon its return stroke, to gradually check 35 the backward movement and ultimately to send the hammer forward again. As long as the hammer is not particularly heavy or the speed of its movement not very great, this dependence upon live air as a buffer is 40 not particularly objectionable, other than that it entails a waste of pressure fluid. When, however, as in the present apparatus, the speed of movement of the hammer or plunger is very great indeed, both on the 45 forward and back strokes, and the plunger is relatively heavy, the momentum of the hammer when returning toward the rear of the device is so great that it actually drives the live air, to the rear of the plunger, back 50 into the pipe or conduit from which it is supplied, and impinges against the rear wall of the casing with dangerous force. In fact,

I have in this manner, previous to my development of the present construction, broken steel bands placed around the rear 55 cap or head, which bands were calculated to sustain a tensile effort of eighteen tons.

This led to the conception and development of the present invention, and I may here state that the herein described implement, 60 the plunger of which weighs twenty-five pounds, can be driven at from 1000 to 1500 forward strokes per minute, each stroke being four and one quarter inches long.

The force of impact against a rock breaking tool is such that solid rock, hard enough to cut glass, is broken away, not in chips, but in large chunks ranging up to three or four inches in diameter; and even more. I have discovered further that when the tool 70 is driven with this violent impetus into the rock, the latter breaks away with but few marks of the tool thereon, while the tool stands up to the work in a manner which at slower speeds of blow is out of the question. 75 In other words, beyond a determined speed, the harder and faster the blows are struck the less injury to the tool.

One of the objects of the present invention therefore is to provide apparatus for 80 so driving tools adapted to cut rock or other difficultly worked material.

Another object of the invention is to greatly increase the efficiency of implements of this character, while minimizing the consumption of air or other pressure fluid.

Still another object is to simplify the construction, and to facilitate the taking apart and replacing or cleaning of parts of the implement, when necessary.

Yet another object is to practically prevent the entrance of dirt and grit into the mechanism, even when used in tunneling operations, and the like, where grit is commonly present in the surrounding atmosphere.

These and other objects of my invention will be hereinafter described and the novel elements and combinations of elements whereby they may be attained will be more particularly set forth in the claims appended hereto.

In the drawings which form a part hereof and in which like reference characters desig-

nate like parts throughout the several views, I have exemplified a preferred form of my novel implement; but it is to be understood that I do not desire to be limited in any way, other than by the scope of the claims, since I am aware of many changes and modifications which may be made herein without departing from the spirit of the invention.

10 Referring to said drawings:

Figure 1 is a longitudinal median section of the said preferred embodiment of my invention.

15 Fig. 2 is a similar view, but showing the plunger in a different position.

Fig. 3 is another longitudinal section taken substantially at right angles to that shown in said Fig. 1.

20 Fig. 4 is a detail cross-section of a sleeve shown in the foregoing figures, the section being drawn to an enlarged scale, and being taken on line IV—IV of Fig. 2.

25 Fig. 5 is a detail cross section of the implement casing, drawn to an enlarged scale, and taken on line V—V of Fig. 1.

Fig. 6 is an enlarged-scale cross section of said casing and assembled parts, taken on line VI—VI of Fig. 1.

30 Fig. 7 is an enlarged-scale detail, longitudinal section of a portion of the implement; the section being taken on line VII—VII of Fig. 6.

Fig. 8 is an enlarged-scale cross section taken on line VIII—VIII of Fig. 7.

35 The implement casing 1 is preferably provided with apertured lugs 2, or corresponding parts, for attaching it to a suitable support; such as the head of a tunneling machine. The rear end of the casing may also be provided with arcuate lugs 3, or other means, for securing the head 4 in place thereon. This head is recessed for the reception of the end of the casing and has claws 5 which may be drawn into engagement with the lugs 4 through the instrumentality of a set screw 6, or the like, which projects through said head into engagement with a cap 7. This cap is preferably made to fit very snugly into a recess 50 or expansion chamber 8 in the rear end of the casing or cylinder, to form an air tight connection therewith. The cap is flanged as at 9 to adapt it for engagement with the extreme end of the cylinder or casing, and in assembling the parts, the head 4 has the claws thereof so positioned with respect to the lugs 3 of the casing that they may be pushed inwardly or downwardly therebetween, the head thereafter being rotated to 55 bring the claws 5 and lugs 3 substantially in alinement as shown in Fig. 6. When the screw 6 is driven into firm engagement with a cap 7, it therefore seats the cap securely in its recess in the casing, the claws 5 being drawn up against the lugs 3. To prevent

any inadvertent lateral displacement of the head with respect to the casing, pins 10 may be driven into suitable apertures in the lugs 3, as shown in Figs. 1 and 6. The head 4 is further so formed as to neatly engage the 70 extremity of the casing all around the same, as at 11. This provides a pocket or exhaust chamber 12 between the cap 7 and the walls of the head 4, the function of which will be hereinafter more fully set forth. The casing is bored for the reception of a plunger or hammer, preferably made from a solid bar of steel, the latter preferably being substantially cylindrical in form, but having a wide groove or recess 13 therearound, at the 80 middle thereof, and further having its rear extremity 14 headed or somewhat larger in diameter than the forward end 15.

The purpose of the groove 13 is two-fold, in that it not only increases the size of the 85 reservoir chamber hereinafter referred to, but also reduces the bearing surface between the plunger and its casing. The plunger should preferably have an oil fit in the cylinder, and I find in practice that about two-thousandths of an inch total clearance is best. The casing is therefore bored as at 16 to correspond with the forward part 15 of the hammer, and is correspondingly bored somewhat larger as at 17 to fit the head 14 95 of the same. Between the walls 16 and 17 the casing may be further recessed as at 18 to form, together with the recess 13 in the hammer, a reservoir chamber for the pressure fluid, the purpose of which will be 100 hereinafter explained.

The casing may be slightly enlarged as at 19 adjacent its rear extremity to afford room for the exhaust ports or conduits 20, 21, these conduits delivering into the exhaust 105 chamber 12 above referred to. The forward end of the casing is preferably conically recessed as at 22 for the reception of a guiding sleeve 23 wherein moves the shank 24 of a tool, broadly designated 25, which latter 110 may be of any suitable description. The tapered sleeve 23 is secured in place in the casing by means of a tapered pin 26, best shown in Fig. 6. To unlock this sleeve therefore it is merely necessary to knock out 115 the pin 26 of the sleeve 23 from the casing. The provision of this removable sleeve is desirable, since wear is apt to occur between the shank of the tool and its guide. The shank 24 of the tool, which in the present 120 instance is square in cross-section, may have an edge thereof notched out as at 27, a pin 28 being driven through the casing and the sleeve 23, across this notch. The casing is bored as at 28 to accommodate the head 29 125 of a port controlling member or sleeve 30, in which is a striking pin or tappet 31. The sleeve 30 is provided with a plurality of cross-ports 32, as best shown in Fig. 7, which when the sleeve is in its outermost position, 130

open into the lateral ports 33 in the walls of the casing. These latter deliver to conduits 34 which preferably extend along opposite sides of the cylindrical casing. Conduits 34 are most conveniently formed by slotting the casing longitudinally thereof to provide not only the port area proper 34, but to also provide under-cut or dove-tailed parts adapted for engagement with cover strips 35. These ports 34 also deliver to the exhaust chamber in the head 4. The sleeve 30 is also preferably annularly recessed or grooved as at 36, so that all the ports 32 are in communication with each other; and a series of ports 37 extend longitudinally through the sleeve from the respective ports 32 to the chamber formed between the forward end 15 of the hammer and the said sleeve. The sleeve immediately back of its head 29 is faceted as at 37', these facets being indicated in dotted lines in Fig. 7, and in full lines in Fig. 4. The purpose of this formation is to invariably admit air to the interior of the casing back of the flange 25 formed by the head 29. In other words, it is never possible for the head of the sleeve to seat itself firmly against the shoulder 38 in the interior of the casing so as to prevent the admission of compressed air or other pressure fluid therebetween. The space thus formed is placed directly in communication with the recess 18 in the casing through the conduits 39 and 40, shown in Figs. 1 and 7. Hence, as long as pressure fluid is admitted to the reservoir chamber above referred to, the sleeve will tend to move toward its outermost position and thereby to drive the tool outwardly before it, through the instrumentality of the head 31 of the striking pin, the latter being normally seated in a recess 42 in the outer face of the sleeve; and it may be here stated that the pressure in the reservoir chamber is normally maintained substantially constant by reason of its connection at all times with the line.

Referring again to the rear end of the casing it will be observed that a plurality of ports or recesses 43 are provided in the wall designated 17, these recesses being preferably relatively quite large in cross-section, as shown in Fig. 5, and extending from the expansion chamber 8 inwardly such a distance as to afford communication between the reservoir chamber and said expansion chamber when the piston head has moved rearwardly substantially to the position shown in Fig. 2. The conduits 43 therefore constitute inlet ports opening into the expansion chamber. Live air is admitted to the reservoir chamber through the vent 44 which extends outwardly through the wall of the casing, a nipple or connection 46 being provided therefor by means 65 of which the device may be coupled to a

pipe or hose adapted to convey pressure fluid, *e. g.*, compressed air, at the pressure at which it is intended to operate the tool. In practice, it may be here stated, I contemplate using from 80 to 100 pounds pressure; but of course do not desire to be limited thereto. The air which exhausts from the implement into the chamber 12 in the manner presently to be described is conveyed away therefrom through a suitable exhaust pipe 47, as shown in Figs. 1 and 2.

The operation of the device is as follows: Assuming that the nipple 46 has been connected to a source of live air, for example, the fluid rushes in and fills the reservoir chamber disposed substantially at the middle of the implement. Since the surface 48 of the hammer or plunger is of greater area than the surface 49 of the same, it is evident that the plunger will normally be driven rearwardly toward the cap 7. Simultaneously, however, the pressure fluid will pass through the conduits 39 and 40 and will then press the sleeve 30 outwardly, thereby driving the tool 25 into its outermost position.

When the sleeve is in this position the ports 32 thereof are in communication with the conduits 40 and hence live air passes inwardly around the striking pin through the ports 37 and fills the chamber in front of the piston or plunger. The latter in the meantime has been urged rearwardly by the pressure of the air against the surface 48, this pressure being supplemented now by the pressure against the forward extremity of the piston, and the latter will hence move rearwardly until it uncovers the forward extremities of the conduits or ports 43, whereupon the live air immediately passes also to the rear of the piston or plunger and balances the pressures above referred to.

As long, therefore, as the sleeve 30 is in its outermost position the piston will thereafter remain inactive. Assuming now that the tool 25 has been brought into engagement with a surface to be operated upon and that the said surface is of rock, or the like. When sufficient pressure has been applied against said surface by the tool, the shank of the latter will be driven back toward and into the casing. This forces the sleeve 30 rearwardly, cutting off connection between the conduits 40 and the chamber in advance of the piston. The continued rearward movement of the sleeve 30 ultimately throws the latter chamber into communication with the ports 33, the pressure fluid then escaping from said chamber through the ports 37, 32, 33 and 34, into the rear or exhaust chamber 12, from whence it is free to flow away from the device through the pipe 47. As this action occurs, however, the pressures upon the respective ends of the piston become unbalanced and the

latter is driven rapidly forward by the compressed air in the expansion chamber, until it impinges against the striking pin. This blow drives the tool abruptly outwardly, but as long as the tool is opposed by sufficiently resistant material, the sleeve will not be allowed to move forward a sufficient distance to throw the ports 32 into communication with the live air conduits 40.

10 The forward movement of the piston, of course, cuts off communication between the reservoir chamber and the expansion chamber, to the rear of the plunger, and the air in said last mentioned chamber thereafter operates expansively until the rear end of the piston uncovers the ports 20, which it does when the plunger has moved nearly into engagement with the striking pin. Thereupon the partially expanded air escapes through the exhaust ports 20 and conduits 21 into the exhaust chamber behind the cap 7, from whence it also escapes through the exhaust pipe 47. It is evident that the very last portion of the stroke of the piston or plunger is made, not under fluid pressure, but owing to the momentum acquired by the plunger. As the surface 48 is at all times subject to the fluid pressure there is, of course, a tendency to urge the plunger again rearwardly, but the momentum of the striking mass is sufficient to overcome this tendency and to enable it to deliver a very powerful blow against the pin 31. In so striking this pin, however, there is a tendency for the plunger to rebound therefrom and this rebounding action is supplemented by the pressure on the surface 48, which results therefore in driving the piston toward the cap 7 at a very high velocity. As the port 43 is again uncovered some live air rushes from the reservoir chamber through to the expansion chamber at the rear of the piston tending to stop the rearward progress of the latter. The momentum acquired by the piston, however, is far more than sufficient to overcome this forward pressure of the so admitted relatively small quantity of live air and the mass plunges toward the cap 7 with but relatively little diminished velocity. The cap 7, as has been stated, is hollow, and its interior walls comprise a cylindrical surface 50, and an outwardly flaring surface 51. The surface 50 is designed to quite closely engage the head 14 of the plunger, preferably having an oil fit therewith, and the rear extremity of the plunger is guided into engagement with this surface by the tapered wall 51. The air within the cap 7 may be, and generally is, to begin with, substantially at the same pressure as is the live air admitted to the reservoir chamber; but it is trapped the moment that the piston head passes the line 52 between the surface 50 and 51; and the continued rearward movement of the piston

compresses this trapped air until the pressure of the same has been raised to possibly double, or even more than that, the pressure of the live air admitted to the implement. It is thus possible to obtain a pressure of from 200 to 250 pounds, or even more, behind the plunger head. Of course, this trapped air continues to be compressed until all momentum has been taken out of the striking mass, whereupon movement of the latter is reversed, and it starts toward the striking pin under pressure very greatly in excess of that of the live air admitted to the mechanism. This trapped air acts expansively and by the time that the rear surface of the plunger reaches the line 52 the trapped air has expanded until its pressure is substantially that of the live air. From this point on, however, for a short distance, live air is freely admitted to the rear of the plunger through the inlet ports 43. As soon as the plunger head passes the forward end of these ports, in the manner above described, this supply of live air is cut off and thereafter the air in the chamber to the rear of the plunger again acts expansively until it is finally exhausted through the ports 20, as per the foregoing. It will be understood, of course, that as long as the tool continues to be pressed inwardly toward the casing with sufficient force to overcome the pressure of live air against the head of the sleeve, the plunger will continue to reciprocate.

I particularly desire to emphasize the fact that what I have endeavored to accomplish in this mechanism appears to be distinctly at variance to common practice in that I endeavor to increase the backward momentum, instead of diminishing the same. In most devices of this description, as heretofore constructed, every effort has been made to destroy this backward momentum at the earliest possible moment, preferably immediately after the plunger has impinged against the striking pin. My mechanism, however, makes use of this momentum; using it to aid in compressing the pressure fluid trapped in the cap 7 in the manner above described, and this action in turn serves to impart a very rapid forward movement to the plunger. In the device illustrated, the air trapping recess in the cap has a depth of about three-quarters of an inch, and while I have not been able to measure it definitely, I have reason to believe that the plunger moves into this recess at least to a depth of from three-eighths to one-half inch. The plunger therefore moves forwardly for a distance of at least three-eighths of an inch under a pressure, for a considerable portion of such distance, above line pressure. Thereafter it moves forward through a distance of one inch or even less on line pressure; at which time the

ports 43 are covered, the air thereafter acting expansively while the plunger travels forward two and one-eighth inches. Finally, the plunger or hammer travels the last 5 portion of its forward stroke under momentum, in the manner above described, the distance so traveled being approximately five-eighths of an inch. I have found in practice that the amount of air which this tool consumes is phenomenally small, and I have recently determined that it is possible to still further decrease the amount of air consumed by decreasing that portion of the stroke of the plunger during which live air 10 is being freely admitted to the rear of the plunger, this distance now being one inch; but it probably being possible to reduce it to one-half inch, or even less, in view of experiments which I have recently made. 15 20 When this implement is used in connection with the proper tool to cut rock, the manner in which the rock is broken away from the tool strikingly illustrates the value of increasing the speed and force with which the 25 tool is driven into the rock; or in other words, it demonstrates the value of greatly increasing the kinetic energy of the striking mass above the recognized practice.

In this connection, also, I may state that 30 when the heads of my machine were broken in the manner above described, I consulted several experts in the art who informed me that the only thing to do was to lengthen the stroke, admitting live air for a longer time 35 so that it might absorb gradually the momentum of the plunger on its backward stroke. This would involve a great waste of air, and this consideration led to the present invention wherein practically no air 40 is wasted, but rather a very marked saving is effected.

A tool operated in accordance with the present invention stands up to its work very 45 many times more satisfactorily than when actuated by a plunger or hammer having a movement more like those commonly used in general practice; and I regard the provision of the pressure fluid trapping chamber at the rear of the plunger as of the 50 very greatest importance in this connection. When the implement is upwardly directed the line pressure not having as yet been turned on, the plunger falls downwardly into the cap. The interior surface of this 55 latter, I should here state, is provided with a pin scratch 53 in order to admit the line pressure back of the plunger when so disposed. This scratch or cut, however, is so small, that it does not permit any 60 considerable amount of the trapped air to escape therethrough when the plunger is being driven rearwardly at the high speed which it attains; being of just sufficient size 65 to allow air under pressure to leak or seep in slowly back of the plunger when the tool

is vertically disposed in the manner described.

In conclusion I desire to point out the advantage of exhausting into a closed cavity, such as that designated 12. This obviates all possibility of dirt or grit from the atmosphere being sucked back into the mechanism. In so far as I am aware no means whatsoever have heretofore been provided to prevent this backward flow of air 75 through exhaust ports, which flow is almost certain to occur where a cavity has been open to the atmosphere and air has been expelled therefrom, said cavity thereafter remaining open for even a short time to the 80 atmosphere during an enlargement of the cavity through the action of the mechanism, as for example, upon the return stroke of the piston or plunger. Where an appliance of this character is used in mining or tunneling the air surrounding it is almost certain to contain fine grit or dirt and such material finds its way into the working parts 85 of the implement in an astonishingly short time. Where these parts have to operate 90 with scant clearances a little of this dirt or grit will speedily suffice to score said parts and reduce the efficiency of the mechanism. I hence regard the provisions of means for excluding this dirt or grit as of very great 95 importance. In illustration of the foregoing remarks in connection with the herein described mechanism, were it not for the provision of the cap 4, upon the return of the plunger from the striking pin and assuming that live air is not being admitted 100 in the chamber in front of the piston owing to the disposition of the sleeve 30, it is evident that the rearward movement of the plunger will create a partial vacuum, at 105 least momentarily, in this forward chamber which will cause air to be sucked in through the conduits 34, 33, 32 and 37, thereby drawing dirt or grit from the surrounding atmosphere directly into the bore of the implement. 110

In some cases, where the dirt in the surrounding air is not excessive, it may suffice to simply exhaust rearwardly to a point relatively remote from the tool, and without 115 the provision of an exhaust chamber or pipe 47; and even this I believe, is contrary to general practice, it being common to eject the air, particularly in front of the piston, directly out toward the tool, the very worst 120 disposition of it that can be made.

Further, the provision of means for carrying away the exhaust pressure, permits of the use of this implement in submarine work; it being obvious that no water can 125 find admission into the tool, owing to this disposition of fluid emerging therefrom.

Finally, I desire to direct attention to the significance of the word "rear" as used in the appended claims. Expressions involv- 130

ing said word are not to be limited by construing the same to mean the rearmost part of the striking mass, for example, but rather to any rearwardly or substantially rearwardly directed surface, no matter in what part of the plunger or striking mass such surface may be disposed, whether toward the forward end, middle portion or back end.

Having described my invention, I claim:

- 10 1. A fluid-pressure operated tool actuating implement, comprising a casing having an inlet and at least one exhaust port, a hammer adapted to be reciprocated by pressure-fluid passing through said inlet port, and a movable port-controlling member which contacts with said exhaust port to close the same when the tool is removed from the work, said inlet port being normally open when said parts are so disposed and the pressure-fluid thereby admitted through said inlet port tending to hold said member in its port closing position, and a substantially closed conduit leading from said implement, said exhaust port opening into said conduit.
- 15 2. A fluid-pressure operated implement comprising a piston, a casing having a reservoir chamber, an inlet port leading therefrom to the front of said piston, and an exhaust port, a port closing member, a striking part adapted to be moved by said member, said piston being adapted to momentarily close said inlet port when operating, and said member being adapted to close said exhaust port.
- 20 3. A fluid pressure operated implement comprising a casing having an inlet port and an exhaust port, a piston, a port closing member, a tool striking part adapted to be moved by said member, said piston being adapted to momentarily close said inlet port of said casing when operating, and said member being adapted to close said exhaust port of said casing.
- 25 4. A fluid pressure operated implement comprising a casing having an inlet port and an exhaust port, a piston, a port closing member, a tool striking part adapted to be moved by said member, and a removable holder for said tool, said piston being adapted to momentarily close said inlet port of said casing when operating, and said member being adapted to close said exhaust port of said casing.
- 30 5. A fluid-pressure operated tool actuating implement which comprises a reservoir chamber, an exhaust chamber and an expansion chamber, the latter of variable size, said implement including a piston one face of which constitutes a wall of said expansion chamber, means controlled by said piston for conveying pressure fluid from said reservoir chamber to said expansion chamber, and from the latter in turn to said exhaust chamber, and tool actuated means for controlling the flow of said fluid.

6. A fluid-pressure operated implement, which comprises means for normally admitting pressure fluid to said implement when inoperative, an expansion chamber of variable size, said implement including a piston one face of which constitutes a wall of said expansion chamber, and a striking part, said implement further comprising a second chamber of variable size, another face of said piston constituting a wall thereof, means controlled by said striking part for controlling the admission of pressure fluid to said last mentioned chamber, and means controlled by said piston for admitting pressure fluid to said expansion chamber.

7. A fluid-pressure operated implement, which comprises means for normally admitting pressure fluid to said implement when inoperative, an expansion chamber of variable size, said implement including a piston one face of which constitutes a wall of said expansion chamber, said implement further comprising two other chambers of variable size, a portion of said piston constituting in each case a wall thereof, means for admitting pressure fluid substantially continuously to one of said chambers when the implement is in use, means controlled by said piston for delivering pressure fluid from said last mentioned chamber to said expansion chamber, and automatic means for admitting pressure fluid to the other of said two chambers when movement of said implement in a determined direction is substantially unopposed.

8. In a fluid pressure operated tool actuating implement, a casing, a piston reciprocably mounted therein and forming a chamber of variable size at one end of said casing, inlet and exhaust ports in said casing leading to said chamber and controlled by said piston, said inlet port being positioned to be opened after said exhaust port has been closed, said extreme end of said chamber forming with said piston a substantially fluid-tight trapping chamber whereby the fluid pressure in the trapping chamber is compressed by the piston, due to its momentum.

9. In a fluid pressure operated tool actuated implement, a casing, a differential piston reciprocably mounted therein and forming therewith chambers to the front and rear of said piston, a source of fluid under pressure, exhaust ports leading from said front and rear chambers, respectively, an intermediate chamber in said casing surrounding the differential shoulder of said piston in communication with said source of fluid under pressure, and a by-pass controlled by said piston connecting said intermediate chamber with said rear chamber, said exhaust port for said rear chamber being also controlled by said piston and positioned to be closed in the rearward travel.

of said piston before the by-pass between the intermediate chamber and the rear chamber is established, said end of said rear chamber forming with said piston a trapping chamber in which the fluid under pressure is compressed upon the completion of the travel of the piston.

In witness whereof, I subscribe my signature, in the presence of two witnesses.
